UNITED STATES PATENT OFFICE.

JOHN B. STRAUSER, OF ALTOONA, PENNSYLVANIA.

FLUE-EXPANDER.

1,072,056.

Specification of Letters Patent.

Patented Sept. 2, 1913.

Application filed October 10, 1911. Serial No. 653,931.

To all whom it may concern:

Be it known that I, JOHN B. STRAUSER, a citizen of the United States, residing at Altoona, in the county of Blair and State of Pennsylvania, have invented certain new and useful Improvements in Flue-Expanders, of which the following is a specification.

This invention relates to flue expanders, wherein rollers are caused to engage the 10 side surface of the flue and expand the same outward, making the flue tight in the flue sheet.

The primary object of the invention is to provide a flue tool having an integral frame 15 coöperating with a plurality of steel rollers adapted to be held in place by steel bands, thus making the tool simple, readily taken apart and easily maintained.

Another object of the device is to provide 20 means for allowing the rollers to freely fall toward the center of the frame, when the roller bar is taken out.

A further object of the device is to provide means for keeping the tool straight, the 25 axis of the tool being perpendicular to the flue sheet into which the flue is being rolled, and at the same time having means for keeping the flue rollers parallel with the flue when the same is in use.

With these and many other objects in 30 view, which will be more readily apparent as the nature of the invention is better understood, the same consists of the novel construction, combination and arrangement of 35 parts, as will be hereinafter fully pointed out, illustrated and claimed.

The essential features of the invention involved, in carrying out the objects above mentioned, are susceptible of a wide range 40 of structural modification without departing from the spirit or scope of the invention, but a preferred and practical embodiment thereof is shown in the accompanying drawings, in which:

Figure 1 is an end elevation of my improved flue roller, showing the rollers and the roller bar in position. Fig. 2 is a side elevation of the parts shown in Fig. 1. Fig. 3 is a side elevation of the flue roller frame. Fig. 4 is a cross section of the roller frame, taken on line 4—4 of Fig. 3. Fig. 5 is a side elevation view of one of the steel rollers. Fig. 6 is a plan view of the top end of one of the steel rollers. Fig. 7 is a top view 55 of one of the retaining rings. Fig. 8 is a side elevation thereof. Fig. 9 is a bottom

plan view of the ferrule. Fig. 10 is a longitudinal sectional view of the ferrule showing the anti-friction washer in position. Fig. 11 is a bottom plan view of the flue 60 guard. Fig. 12 is a sectional view of the same. Fig. 13 is an elevation of the dowel pin, and Fig. 14 is an end view thereof.

Like reference numerals designate corresponding parts throughout the several figures of the drawings.

This improved flue roller designated in its entirety by the numeral 10, essentially consists of a frame 11, provided with a central opening 12, a plurality of spaced segments 70 or posts 13, between which rollers 14 occupy a spaced relation, also journals 15, engaging the notches 16, in the frame 11, said rollers 14 being held in operative relation by the spring retaining rings 17, adapted to 75 fit in the grooves 18 in the frame, as clearly illustrated in Fig. 3 of the drawings.

This improved tool further consists of a roller bar 19, adapted to pass through the opening 12 and engage the rollers 14, and 80 force the same out radially, as shown in Fig. 1 of the drawings.

In order to insure the rollers engaging the flue with their proper relation, a flue guard 34 is provided, having a central opening 20, 85 through which the solid stem 21 of the frame protrudes, a recess 22 which receives the collar 23, thus keeping the parts in operative relation. The guard 34 is further provided with a plurality of spaced segmental legs 24, 90 the inside face 25 of which is adapted to rest against the face of the flue sheet, into which the flue is being rolled.

In order to keep the frame, together with the rollers, from entering the mouth of the flue too far for the proper rolling of the flue, the ferrule 26 is provided, having a recess 27 into which is fitted the friction ring 28, which bears against the face 29 of the flue guard 34. This friction ring is preferably made of hard brass, or material of similar nature.

The ferrule 26 is locked to the frame 11 by the dowel pin 30, which passes through the hole 31 of the ferrule and a hole 32 of 105 like diameter, located on the top of the stem 21.

The rings 17, which hold the rollers in position are preferably made of steel, the ends feathered and left unwelded to provide 110 means for placing the same in position.

The operation of this flue expander may

be described as follows: The point 33 of the frame is placed in the mouth of the flue, and the face 25 of the flue guard made to rest against the face of the flue sheet, after which 5 the roller bar 19 is placed in position. The placing of the roller bar tends to force the rollers out against the inside face of the flue; the bar being tapered and, likewise, the rollers, naturally the further the bar enters the 10 frame, the further the rollers rotate outward, forcing the flue out against the flue sheet, and as I provide the ends 34 of the rollers 14, with rounded corners, the flue is not cut when rolled into place. The manner 15 of keeping these rollers in position freely admits of the interchange with rollers of larger diameter if desired.

Without further description and elaboration it is thought that the many advantages 20 of the herein described flue expander are readily apparent, and what I claim is:

A flue expander comprising a roller carrying frame having a central bore extending throughout its length, the body of which is 25 provided with circumferential grooves whose bottoms have notches, spaced apart segmental posts formed between said grooves

and parallel to the axis of the frame, a stem portion of the frame, a collar formed at the junction of the latter with the body of the frame, rollers located between the spaced apart posts and having journals bearing in said notches, spring retaining rings fitting in the grooves in the frame body to hold the rollers in position, a flue guard fitted over 30 the stem portion and having a circular recess receiving the collar between the body and stem of the frame, a ferrule having a central opening and a circular recess on its bottom face adjacent thereto, a ring of anti-friction material fitted within said recess, said ferrule being fitted over the stem and locked thereto so that the anti-friction ring abuts against the rear face of the flue guard, and a roller bar extending through 40 the central bore of the frame for forcing the rollers outwardly.

In testimony whereof I hereunto affix my signature in the presence of two witnesses.

JOHN B. STRAUSER.
